UNITED STATES PATENT OFFICE.

FREDERICK C. BAKER, OF PORTLAND, OREGON.

LIGHTING FIXTURE.

1,420,806.

Specification of Letters Patent. Patented June 27, 1922.

Application filed April 1, 1918. Serial No. 225,958.

To all whom it may concern:

Be it known that I, FREDERICK C. BAKER, a citizen of the United States, residing at Portland, in the county of Multnomah and 5 State of Oregon, have invented a certain new and useful Improvement in Lighting Fixtures, of which the following is a specification.

My invention relates to that class of fixtures known as semi-indirect lighting fixtures, and has for its object to provide an improved means for supporting the shield for the light in conjunction with the reflector.

15 My means of accomplishing the foregoing objects may be more readily understood by having reference to the accompanying drawings which are hereunto annexed and are a part of this specification, in which,

20 Fig. 1 is an elevation partly in section of my improved fixture.

As shown in the drawings, 2 indicates the canopy which is of the usual construction, from which depends chains 3, which extend 25 to an annular frame 4 being secured thereto, by means of an eye bolt 5 in the usual manner. This frame is provided with a circumferential flange 7 at its lower portion, forming a shoulder which is adapted to support 30 the glass reflector 8, a central chain 9 having a socket 10 secured to its lower end which supports an electric light bulb 11, is within the shield 12 which, in this instance, is a glass bowl. This bowl is suspended by 35 a spider comprising a plurality of chains 13 which extend from a spun ring 14 adapted to fit inside of the center 15 of the reflector 8.

The reflector 8 is of conoidal form and has 40 at its center, an opening through which the lamp socket and bowl supporting shell extends, the spun ring 14 being turned outwardly so as to rest upon the annular lip 15 on the reflector.

It will be apparent from the foregoing 45 description that none of the direct rays of light can pass from the filament to the eye of the observer, but will be re-directed from the inner surface of the shield 12 to the reflector 8, where they in turn, will be reflected down to the useful or working plane.

It will be apparent that a portion of the 50 light rays will pass directly through the bowl 12, diffusing a soft light directly under the fixture where it is most desired.

Having described my invention, what I regard as new and desire to secure by Letters Patent, is:

1. In a lighting fixture, the combination 60 with a reflector, a canopy, an annular frame secured to said canopy, chains depending from said canopy and secured to said frame and extending thereto, a shoulder formed on said frame adapted to support said reflector, a central chain, a socket secured to its lower end, an electric light bulb supported by said socket, a shield, a spider which supports said shield, and having a ring adapted to fit inside of the center of said reflector.

2. In a lighting fixture the combination 70 with a conoidal reflector having a central opening therein, a canopy an annular frame secured to said canopy provided with a circumferential flange at its lower portion, chains depending from said canopy and secured to said frame and extending thereto, a shoulder formed by said flange adapted to support said reflector, a chain, a socket secured to its lower end, an electric light bulb supported by said socket, a shield, a 75 spider having a ring which suspends said shield, an annular lip on said reflector, said ring adapted to fit inside of the center of the reflector which rests on said lip.

In testimony whereof I have signed the 85 foregoing specification.

FREDERICK C. BAKER.
